SPARK PLUG

Joseph O. C. di Tona, Newark, N. J.

Application March 23, 1944, Serial No 527,715

7 Claims. (Cl. 123—169)

This invention relates to improvements in spark plugs.

The primary object of the invention resides in a spark plug in which the same is sealed against the leakage of combustible fuel gases therethrough, thus preventing loss of compression when the spark plug is in use upon an internal combustion engine.

Another feature of the invention is to provide a sealed spark plug which is simple of construction and assembly, inexpensive to manufacture, and strong and durable to withstand the extreme temperatures and pressure when in use.

Other novel features of the invention will become apparent as the following specification is read in conjunction with the accompanying drawing, in which,

Figure 1 is a side elevational view of my improved spark plug, the terminal clamping nut being shown in dotted lines.

Figure 2 is an enlarged vertical longitudinal sectional view taken on the line 2—2 of Figure 1.

Figure 3 is an enlarged horizontal sectional view on the line 3—3 of Figure 1.

Referring to the drawing by reference characters, the numeral 10 designates my improved spark plug in its entirety. The spark plug 10 comprises a conventional spark plug shell or plug base 11, the same being made of metal and comprising an externally screw-threaded body portion 12 and a reduced screw-threaded plug portion 13, there being a flange or shoulder 14 intermediate the portions 12 and 13. The plug-like body 11 is provided with an axial stepped bore which consists of an inner bore portion 15 and a reduced bore portion 16, the stepped portion constituting a shouldered seat 17. A ground electrode 18 is provided at the outer end of the reduced bore portion 16. The inner face of the base member 11 is provided with an annular groove 19 which is concentric to the bore and is disposed adjacent the enlarged portion 15 thereon. Seated in the groove 19 is one end of a collar 20, said collar being of metal to which glass may be bonded for reasons to be hereinafter explained. That portion of the collar 20 which is seated in the groove 19 is brazed to the base member 11 to provide a rigid sealed joint therebetween. The base member 11 and the collar 20 constitute a single unit for reasons of assembly.

A second assembly unit consists of the lead or central electrode 21 which carries a metal cup-shaped member 22. The electrode 21 comprises a cylindrical body portion 23, a reduced threaded extension 24 and a reduced cylindrical stem portion 25, the free terminal end of the portion 25 being provided with a tungsten sparking tip 26. The cup-shaped member 22, like the collar 20, is made of a metal to which glass may be bonded, the end wall of the cup-shaped member 22 hav-

ing a central opening through which the body portion 23 of the electrode passes, said cup-shaped member being brazed to the portion 23 to provide a rigid sealed joint.

5 The numeral 27 designates an inner insulating core made of any well known refractory material capable of withstanding temperatures above 1800° F. without undergoing physical or chemical changes. The core 27 is molded and is provided with an axial bore 28 which extends the length thereof. The main body portion of the core 27 is of a diameter to fit into the enlarged bore portion 15 and is provided with a reduced downwardly tapered portion 29 which extends 10 into the reduced bore portion 16. The body portion of the core 27 and the reduced portion 29 form a shoulder 30 which is complementary to the shouldered seat 17. A copper sealing washer 31 is interposed between the shoulder 30 and the seat 17 for sealing the joint therebetween. The washer 31 is preferably constructed of beryllium copper although other equivalent materials may be used in lieu thereof.

15 The reduced stem portion 25 of the central electrode 21 extends through the bore 28 of the core 27 with the tip end 26 extending beyond the lower end of the core and in suitable spaced 20 sparking distance from the ground electrode 26, the space between the electrodes constituting the 25 sparking gap. The upper end of the bore 28 is slightly enlarged to provide a shouldered seat 32 which is confronted by shoulder 33 formed between the body portion 23 and the reduced stem 25 of the central electrode. A copper sealing 30 washer 34 is interposed between the shoulder 33 and the seat 32 to seal the joint therebetween. The copper washer 34 might also be made of beryllium or equivalent material.

35 With the parts in the assembled position so far 40 described, it will be noted that the annular side wall or flange 35 of the cup-shaped member 22 is in spaced confronting and concentric relation with respect to the metal collar 20. Bonded to the flange 35 and collar 20 are the respective 45 ends of a glass connecting sleeve 36. The bonds between the glass sleeve and the flange 35 and collar 20 are airtight whereupon the space between the inner core 27 and sleeve 36 is hermetically sealed.

50 Screwed to the threaded portion 12 is one end of an outer metal protecting shield or casing 37, the other end of said shield being externally screw-threaded as at 38. Interposed between the protecting shield 37 and the glass sleeve 36 is the cylindrical skirt portion 39 of an outer insulating core 40 which is also constructed of a refractory material capable of withstanding high temperatures. The upper end of the core 40 is provided with an annular flange 41 which rests upon the upper edge of the outer casing 37. The

outer core 40 is provided with a central passage 42 through which the body portion 23 of the central electrode passes. For the purpose of holding the core 40 in position and for closing the upper end of the protective casing 37 there is a plastic insulating cap 43, the same being screwed to the threaded portion 38. The cap 43 is provided with a central opening 44 through which the outer threaded end 24 of the electrode 23 passes. A clamping nut or snap adapter for a lead wire 10 is applied to the threaded portion 24, such clamping nut being shown in dotted lines at 45 in Figure 1.

From the foregoing description, it is seen that I have provided a spark plug for internal combustion engines in which the joints between the parts are sealed against the escape of fuel gases during the compression stroke of the motor. The parts and joints are of sufficient strength to withstand the extreme temperatures and pressures to which they are exposed during use.

While I have referred to certain of the parts as being constructed of specific materials, the materials may vary without in any way departing from the scope of the invention set forth in the appended claims.

Having thus described the invention, what I claim as new and desire to secure by Letters Patent, is:

1. A spark plug comprising a screw base having a ground electrode, a casing having one of its ends threaded to said base, an end closure threaded to the other end of said casing, a lead electrode mounted axially within said casing having one of its ends in spaced relation to the ground electrode and its other end extending beyond said end closure, insulating means within said casing for shielding said lead electrode, and a sealed chamber within said casing between the base and the end closure through which said 40 lead electrode passes.

2. A spark plug comprising a screw base having a stepped central bore therein, the stepped portion constituting a shoulder seat, a ground electrode on said base, an insulating core having a shoulder in sealing relation to the shoulder seat, said core having an axial bore extending the length thereof, a lead electrode extending through said axial bore having its inner end in spaced relation to said ground electrode and its outer end extending beyond the outer end of the core, a fixed concentric collar extending inwardly from the base in spaced relation to said core, a cup-shaped member fixedly secured to the lead electrode with its open side disposed in confronting relation to said collar and spaced therefrom, and a glass sleeve having its ends respectively connected and sealed to the collar and cup-shaped member and spaced from said core.

3. A spark plug as set forth in claim 2 including an outer protecting shield having one end threaded to the base, said shield being spaced from the sleeve in surrounding relation, and a cap threaded to the other end of the shield having a central aperture for the passage of the outer end of the lead electrode.

4. A spark plug as set forth in claim 2 including an outer shield casing having its inner end threaded to the base, a hollow outer insulating core mounted within said casing in spaced relation thereto and in spaced encircling relation to the sleeve, and a cap threaded to the outer end of said casing, said outer core and cap having

aligned central apertures for the passage of the outer end of the lead electrode.

5. A spark plug comprising a metal screw base having a stepped central bore extending therethrough, the stepped portion constituting a shoulder seat, the inner end of the base having a groove therein concentric to said bore, a metal collar having its inner end seated in said groove and fixedly sealed to the base, an inner insulating core having a central bore extending therethrough, said inner core having a reduced inner end portion, the reduced end portion defining a shoulder disposed in confronting relation to the shoulder seat, a sealing washer interposed between the shoulder and said shoulder seat, a central electrode having a reduced portion extending through the bore in said inner core, the free end of the reduced portion constituting a sparking tip, a ground electrode on said base in spaced relation to the sparking tip of the central electrode, the reduced portion of the central electrode defining a shoulder, a shouldered seat provided on the outer end of the inner core in confronting relation to the shoulder on the electrode, a sealing washer interposed between the last-mentioned shoulder and shoulder seat, a metal cup-shaped member integrally connected to said central electrode concentric thereto with its open side arranged in spaced confronting relation to said collar, a glass sleeve having its respective ends sealingly connected to the cup-shaped member and to the collar, said glass sleeve surrounding the inner core in spaced relation thereto, an outer insulating core surrounding said glass sleeve and having a flange seated on the outer end of the casing, a shield casing having its inner end threaded to said screw base, and an insulating cap threaded to the outer end of said casing in clamping engagement with the outer core, said outer core and cap having aligned apertures therein for the passage of the outer end of the central electrode.

6. In a spark plug, a screw base having a central bore therein and a ground electrode at the outer end thereof, an insulating core having an axial bore extending the length thereof and its lower end extending into said bore, sealing means between said core and the walls of said bore, a lead electrode extending through said axial bore having its lower end disposed in spaced relation to said ground electrode and its other end extending beyond the outer end of the core, a fixed concentric collar extending upwardly from the base in spaced relation to said core, a cup-shaped member fixedly secured to said lead electrode with its open side disposed downwardly in confronting relation to said collar and spaced therefrom, and a glass sleeve having its ends respectively connected and sealed to the collar and cup-shaped member and spaced from said core.

7. In a spark plug as set forth in claim 6, including a cylindrical casing having its lower end threaded to said screw base and disposed in spaced concentric relation to the glass sleeve, a cylindrical insulating member telescoping the sleeve having its lower end abutting the screw base, an annular flange at the upper end of the insulating member overlying the top edge of said casing, and a cap threaded to the upper end of the casing and forcibly bearing against the top of the insulating member to hold the lower end thereof tight against the screw base.

JOSEPH O. C. DI TONA.
